C. M. AUMENT.
BOOK COVER PROTECTOR.
APPLICATION FILED NOV. 6, 1915.

1,220,389.

Patented Mar. 27, 1917.

Inventor
Carroll M. Aument.

UNITED STATES PATENT OFFICE.

CARROLL M. AUMENT, OF STRASBURG, PENNSYLVANIA.

BOOK-COVER PROTECTOR.

1,220,389.

Specification of Letters Patent.

Patented Mar. 27, 1917.

Application filed November 6, 1915. Serial No. 59,955.

To all whom it may concern:

Be it known that I, CARROLL M. AUMENT, a citizen of the United States, and resident of Strasburg, in the county of Lancaster and 5 State of Pennsylvania, have invented a new and useful Book-Cover Protector, of which the following is a full and clear specification.

My invention particularly relates to a 10 book-cover protector for any book or pamphlet, but is particularly useful in protecting books used in schools, colleges, etc.

In the majority of the public schools of 15 the country, books for the students are supplied by the school board, and to increase the life of the books as well as provide for sanitary requirements, it is the practice to cover all school books with a paper protector or outer cover. This work of covering the 20 books is frequently done by the students, either at school or at home, with the result that a good deal of the students' time is consumed and the resulting covered books are far from uniform. The covering of the 25 books is particularly necessary because they are transferred to different students a number of times, depending upon the life of the books.

The purpose of the present invention is to 30 provide a bound book with a cover protector that will avoid the necessity of using a home-made cover protector and which will lend uniformity to the appearance of the school books and increase the length of service. 35

In its simplest form, the improved book cover protector comprises a protector sheet permanently attached at one or more points to the book cover and provided with means 40 for facilitating its removal when it becomes worn or soiled.

In its more practical and useful form, the invention includes such a book cover protector formed of a plurality of superimposed sheets of proper material permanently 45 attached to the cover at one or more points and completely inclosing the cover. The means for facilitating the removal of the protector from the book cover comprise weakened lines or portions of the protecting material by which the material can be neatly torn away and removed from the book cover. Any suitable device may be employed for this purpose including scored lines or perforations and wherever such expressions as 50 "scored line", "perforations", "separating

lines" and the like are employed in the claims, such term is intended to indicate any device of this character which is intended to confine the tearing action to a predetermined line extending between a major portion which is to be removed from the book and a minor portion from which said major portion is removed. In the form embodying 60 a plurality of cover protector sheets, it is preferred to have the weakened lines or zones of the sheets out of register with each other, so as to avoid the danger of removing more than one protector sheet at a time. It has been found desirable to also provide 65 each of the plurality of protector sheets with a perforation into which a sharp instrument can be inserted for starting the tearing of the protector sheet from the cover, and in case of using these starting openings it is 70 preferred that the openings of the several sheets be placed out of register with each other. 75

By reason of having the same style cover on the books of all students, the color, size and 80 general appearance will be more pleasing due to this uniformity.

The above and other objects and advantages of my improvement will fully appear 85 from the following description taken in connection with the accompanying drawings and be explicitly defined in the appended claim. I wish it understood, however, that this disclosure is illustrative only and that the principle of my invention can be embodied in 90 constructions other than the one specified herein.

On the drawings in which similar parts are referred to by the same reference characters,

Figure 1 shows the book-cover protector applied to a book.

Fig. 2 is a highly magnified view, showing the several covers and how they may be quickly removed.

Fig. 3 is a perspective view showing the several superimposed covers.

In the drawings, an ordinary bound book with stiff covers hinged to the back is shown in the usual way. In binding such books 105 the common practice is to provide such book of leaves with strengthened cover-attaching sheets for fly leaves which are glued to the previously prepared cover for securing the book in the cover.

In preparing a bound book with the improved cover protector, I propose to mount

one or a number of protector sheets upon the previously prepared book cover in such manner that the fly leaf of the book will be glued to the inside of the book cover after 5 the protector is in place. In accomplishing this the protector is permanently secured upon the book at one or more points without interfering with the removability of the main body of the protector when it becomes 10 worn or soiled.

In producing the cover protector, suitably blanked out sheets of proper material are prepared with weakened lines formed by scoring or perforating, these weakened lines 15 being located with proper regard to their desired position with reference to the book cover when the protector is folded and secured thereon.

The drawing shows a cover protector 20 made up of three superimposed sheets or layers. After the book is ready for covering, I take the inner paper cover protector and secure it to the inner cover of the book itself along a line or at certain points. This 25 may be done by gluing or other securing means. This gluing or other securing means goes as far as a certain line and then the rest of the cover protector is free to be torn off by the insertion of a knife, finger-nail or 30 other suitable means. After the inner cover protector has been secured to the binding of the book, the next one is secured or superimposed over that cover protector. The line of gluing and the tearing or apertured space 35 is not directly placed over the tearing line of the first cover protector, but is purposely made some slight distance away so that two covers will not be accidentally torn simultaneously. This is clearly shown in Fig. 2.

40 At 10 is shown a book with 11 shown as the back of the book. 12 is a fly wheel pasted to the book in the usual way. The numerals 14, 15 and 16 indicate book-cover protectors. Book-cover protector 14 has a 45 slot 7. 15 has a slot 6, and 16 has a slot 5. Each cover protector 14, 15 and 16 has an apertured or weakened line 19, 18 and 17 respectively. Cover 14 or the inner cover protector is not pasted to the back of the 50 book 11 at 21 and 22, only at 20, thus I have only a thin edge of pasting around the inside of the back of the book 11. It is apparent that when the outside cover 16 is removed by inserting an implement in slot 55 5, that the cover will be removed along apertured line 17. Should an implement be inserted in apertured line 17 to facilitate the

removal along weakened line 17, it could not possibly injure or mar the next cover protector 15. Similarly the removal of the 60 second cover protector could not injure the lower protector 14.

After the outer cover protector has become soiled or worn, it can be removed by inserting a pointed instrument in the tearing hole 65 5 and tearing or cutting the protector sheet from the book. The weakened or perforated lines 17, 18 and 19 serve to define the tearing edges of each cover protector so as to insure a neat result to the 70 removing operation. This is clearly shown in Fig. 2. When the outer protector is removed, the book will have the next inner protector sheet presented to form an entirely new, sanitary and clean cover 75 protector.

While I have shown an improved book cover protector consisting of only three superimposed sheets, it will be clear that any practical number of such protector 80 sheets can be employed, the number desired depending largely upon the length of life of book from other standpoints.

From the foregoing description taken in connection with the accompanying drawings, the advantages of the construction and mode of operation will be readily understood by those skilled in the art to which the invention appertains. While I have described the principle of operation together with the 90 form which I now consider to be the best embodiment thereof, I desire to have it understood that the device shown is merely 95 illustrative and that such changes may be made when desired as fall within the scope of the appended claim.

Having described my invention what I believe to be new and desire to protect by Letters Patent, is:

The combination with a bound book, of 100 a plurality of superimposed cover protectors each provided with a portion secured between the inside of the cover and a fly leaf secured thereto, said fly leaf covering and holding the extreme outer edge of each of 105 said protectors, said cover protectors being provided with means adapting other portions covering the outer surface of the book cover to be readily detached, each of said cover protectors being provided with an 110 elongated slit running at and along the lower edge thereof, said slits being out of register with each other.

CARROLL M. AUMENT.
